LATCH BOLT HOLDBACK

Charles Ledin and Philip T. Krause,
Stamford, Conn.

Application February 1, 1944, Serial No. 520,590

9 Claims. (Cl. 292—169)

This invention relates to a hold back for use with a latch bolt. More particularly, this invention relates to a hold back for use with a night latch.

Latches, and more particularly night latches, are generally equipped with latch bolts that are spring projected and are adapted to be retracted by a thumb turn or the equivalent thereof. Since such latches are generally used as auxiliary latching devices, it is desirable that some means be utilized for maintaining the latch bolt in a retracted hold back position until it is released for projection by its spring.

For the particular purpose, the art discloses many devices including push and pull buttons, these buttons being generally mounted for access outside the casing of the night latch.

Our invention relates to a hold back device that very closely resembles in outward appearance some of the prior art structures, but which is exceedingly simple to actuate and to release.

For a description of our invention we shall refer to the drawings wherein Fig. 1 is a perspective view of a night latch to which our invention is applied. Fig. 2 is a view looking at the back of the night latch of Fig. 1 with the rear plate removed. Fig. 3 is a section taken along lines 3—3 of Fig. 2. Fig. 4 is a section taken along lines 4—4 of Fig. 3. Fig. 5 is a view similar to Fig. 3 showing the latch bolt in its hold back position. Fig. 6 is a view similar to Fig. 2 but illustrating a modified form of the invention in which the hold back device is mounted within the thumb turn that is used to retract the latch bolt. Fig. 7 is a section taken along lines 7—7 of Fig. 6. Fig. 8 is a view similar to Fig. 6 but showing the parts in the hold back position of the latch bolt. Fig. 9 is a view of certain parts of Fig. 7 showing the latch bolt in its hold back position.

Referring now more particularly to the drawings, and especially Figs. 1—5 inclusive, the latch casing of our invention is designated by reference numeral 10 while the latch bolt mounted thereon is designated by reference numeral 11. The latch bolt is projected by a spring 12 in a conventional manner and is retracted by the pin 13 extending from a cam plate 14, that is secured as a part of a thumb turn 15. As those skilled in the art will readily appreciate, the structure thus far set forth is entirely conventional and is not necessarily our invention claimed herein.

The hold back forming our invention may take various forms but we prefer to use that type that is shown in Figs. 1—5. In those figures the hold back is shown comprising a push button 16

mounted in a compound bore 17 formed in the casing 10, the inner end of the push button being riveted at 18 to a hold back plate 19 and a plate spring 20 that are within the casing 10.

As is clearly shown in Fig. 4, the plate spring 20 has its opposed ends 21 resting within slots 22 formed in the casing, and urges the push button 16 to its outer release position of Fig. 3. In this position of the parts, a detent lug 23 that is part of the hold back plate 19, is located below an ear 24 bent downwardly from the plate portion 25 of the latch bolt 11. With the latch bolt projected as in Figs. 1, 2 and 3, it may be retracted by rotation of the thumb turn to the position of Fig. 5, thereby bringing ear 24 of the latch bolt into its dotted line position of Fig. 5. In this position of the ear 24, the push button 16 may be depressed from its dotted line position of Fig. 5 to its full line position, and the latch bolt then released for projection. The latch bolt will move only until the ear 24 reaches its full line position of Fig. 5, with the detent lug 23 of the hold back plate 19 within the undercut notch 26 formed in the said ear.

It is now obvious that the latch bolt will be held in its hold back position by the push button 16 and its hold back plate 19. It is also obvious that the latch bolt ear 24 will hold the push button 16 against movement to its release position by plate spring 20, due to the interlocking engagement of the detent lug 23 with notch 26 of ear 24.

If now it is desired to project the latch bolt to its position of Fig. 1, it is not necessary to actuate the push button 16 manually. It is only necessary to rotate the thumb turn 15 whereby to retract the latch bolt beyond its hold back position to bring the ear 24 to its dotted line position of Fig. 5. Spring plate 20 will then project the push button 16 to its position of Figs. 3 and 4 away from ear 24, and upon release of the thumb turn 15 the latch bolt will spring outwardly.

In that form of our invention illustrated in Figs. 6—9 inclusive, the hold back operating push button is mounted for sliding movement within a thumb turn 30 rather than in a bore of the casing as in the first modification. In the modification of Figs. 6—9, the push button is designated by reference numeral 31 and it is urged to an outward release position by a spring 32 mounted about a guide pin 33 that is fixed to the push button and slides within a bore 34 in a casting 35 forming part of the body of the thumb turn 30, as is well illustrated in the drawings.

The push button 31 has a pin 36 extending therefrom into the casting 10a of the latch bolt,

and said pin 36 is formed with a notch 37 adapted to interlock with the lug 38 of the plate 39 of the latch bolt 40. Thus, if the latch bolt is retracted by thumb turn 30 through its cam pin 30a, to bring the lug 38 beyond the end of the pin 36, the push button 31 may be depressed to the position of Fig. 9. If the latch bolt is then released for projection by its spring 12a, the lug 38 will enter the notch 37 of the pin 36. This will effectively block the movement of the latch bolt from its hold back position to its projected position and will simultaneously retain the push button 31 in its hold back position of Figs. 8 and 9.

If it is now desired to allow projection of the latch bolt, it is only necessary to retract the latch bolt beyond its hold back position of Figs. 8 and 9, withdrawing the lug 38 of latch bolt plate 39 from the notch 37 of pin 36. The pin 36 and push button 31 will then be spring projected to the release position of Fig. 7, and the latch bolt when released by thumb turn 30 will spring outwardly to its position of Figs. 6 and 7.

We believe that the operation and construction of our invention will now be apparent to those skilled in the art.

We now claim:

1. In a lock of the class described, a casing, a latchbolt slidable on said casing from a projected to a retracted position, a spring urging said latchbolt to its projected position, a push button, means mounting said push button for inward and outward sliding movement relatively to said casing, a spring pressing said push button outwardly relatively to said casing, means movable with said push button adapted to prevent movement of said latchbolt by said latchbolt spring from a retracted hold back position to its projected position when said push button is in its inward position relatively to said casing, and means whereby said latchbolt presses against the means movable with said push button to retain said push button in said inward position until said latchbolt is retracted beyond said retracted hold back position.

2. In a lock of the class described, a casing, a latchbolt slidable on said casing from a projected to a retracted position, a spring urging said latchbolt to its projected position, a hold back button, means mounting said button for movement relatively to said casing, a spring pressing said button into a release position, means movable with said button against the force of said button spring into hold back position to prevent movement of said latchbolt by said latch bolt spring from a retracted hold back position to a projected position, and a part of said latchbolt engaging said means whereby said latchbolt holds said hold back button against movement to release position.

3. In a lock of the class described, a casing, a latchbolt slidable on said casing from a projected to a retracted position, a spring urging said latch bolt to its projected position, a hold back button, means mounting said button for movement relatively to said casing, a spring pressing said button into a release position, means movable with said button against the force of said button spring into hold back position to prevent movement of said latch bolt by said latch bolt spring from a retracted hold back position to a projected position, and a part of said latchbolt engaging said means whereby said latchbolt holds said hold back button against movement to release position, the retraction of said latchbolt beyond its hold back position releasing said hold back but-

ton for movement by its spring to its release position.

4. In a lock of the class described, a casing, a latchbolt slidable on said casing from a projected to a retracted position, a spring urging said latchbolt to its projected position, a push button mounted for sliding movement in a bore in said casing with the head of the push button exposed on the outside of the casing, a spring pressing said button outwardly of said casing into release position, means movable with said button against the force of said button spring inwardly of said bore into hold back position to prevent movement of said latchbolt by said latch bolt spring from a retracted hold back position to a projected position, and a part of said latchbolt engaging said means whereby said latchbolt holds said push button against movement outwardly of said bore to said release position.

5. In a lock of the class described, a casing, a latchbolt slidable on said casing from a projected to a retracted position, a spring urging said latchbolt to its projected position, a push button mounted for sliding movement in a bore in said casing with the head of the push button exposed on the outside of the casing, a spring pressing said button outwardly of said casing into release position, means movable with said button inwardly of said bore against the force of said button spring into hold back position to prevent movement of said latchbolt by said latch bolt spring from a retracted hold back position to a projected position, and a part of said latchbolt engaging said means whereby said latchbolt holds said push button against movement outwardly of said bore to said release position, the retraction of said latchbolt beyond its hold back position releasing said push button for movement by its spring to its release position.

6. In a lock of the class described, a casing, a latchbolt slidable on said casing from a projected to a retracted position, a spring urging said latchbolt to its projected position, a thumb turn mounted for rotation on said casing, means rotatable with said thumb turn for retracting said latchbolt, a hold back button, means mounting said hold back button on said thumb turn with a part of said button extending inwardly of said casing, a spring pressing said button relatively to said thumb turn into a release position, means movable with said button against the force of said button spring into hold back position to prevent movement of said latch bolt by said latchbolt spring from a retracted hold back position to a projected position, and a part of said latchbolt engaging said means whereby said latchbolt holds said hold back button against movement to release position.

7. In a lock of the class described, a casing, a latchbolt slidable on said casing from a projected to a retracted position, a spring urging said latchbolt to its projected position, a thumb turn mounted for rotation on said casing, means rotatable with said thumb turn for retracting said latchbolt, a hold back button, means mounting said hold back button on said thumb turn with a part of said button extending inwardly of said casing, a spring pressing said button relatively to said thumb turn into a release position, means movable with said button against the force of said button spring into hold back position to prevent movement of said latchbolt by said latchbolt spring from a retracted hold back position to a projected position, and a part of said latchbolt engaging said means whereby said latchbolt holds

said hold back button against movement to release position, the retraction of said latchbolt beyond its hold back position releasing said hold back button for movement by its spring to said release position.

8. In a lock of the class described, a casing, a latchbolt slideable on said casing from a projected to a retracted position, a spring urging said latchbolt to its projected position, a thumb turn mounted for rotation on said casing, means rotatable with said thumb turn for retracting said latchbolt, a hold back button, means mounting said hold back button in a bore of said thumb turn for inward and outward sliding movement with a part of said hold back button extending inwardly of said casing and the head of said hold back button exposed outwardly of said thumb turn bore for depression, a spring pressing said button outwardly of said thumb turn bore into release position, means movable with said button against the force of said button spring into hold back position to prevent movement of said latchbolt by said latchbolt spring from a retracted hold back position to a projected position, and a part of said latchbolt engaging said means whereby said latchbolt holds said hold back against movement to said release position.

9. In a lock of the class described, a casing, a latchbolt slideable on said casing from a projected to a retracted position, a spring urging said latchbolt to its projected position, a thumb turn mounted for rotation on said casing, means rotatable with said thumb turn for retracting said latchbolt, a hold back button, means mounting said hold back button in a bore of said thumb turn for inward and outward sliding movement with a part of said hold back button extending inwardly of said casing and the head of said hold back button exposed outwardly of said thumb turn bore for depression, a spring pressing said button outwardly of said thumb turn bore into release position, means movable with said button against the force of said button spring into hold back position to prevent movement of said latchbolt by said latchbolt spring from a retracted hold back position to a projected position, a part of said latchbolt engaging said means whereby said latchbolt holds said hold back button against movement to said release position, the retraction of said latchbolt by said thumb turn releasing said button for movement to said release position.
